REVERSIBLE HEEL

Roosevelt Alexander Hayden, Chicago, Ill., assignor of one-third to Harry Hardy, one-third to Norman Brown, and one-third to Chester W. Brown, all of Chicago, Ill.

Application July 31, 1939, Serial No. 287,530

4 Claims. (Cl. 36—39)

An object of my invention is to provide a reversible heel for shoes which can be readily reversed when it becomes worn, and thus the useful life of the heel is considerably lengthened.

5 A further object is to provide one form of heel which is circular in outline and can be rotated to as many as four different positions, whereby the useful life of the heel is increased substantially fourfold.

10 Another object is to provide a heel and means for readily connecting it and disconnecting it relative to the heel portion of a shoe so that it can be readily removed and replaced or turned so that further wear will occur at a different portion of 15 the heel as desired.

Another important object of my invention is to provide means to prevent undesired rotation of the heel after it is once adjusted on the shoe.

In the accompanying drawing I have shown a 20 preferred embodiment of my invention and one modification thereof. The drawing is not intended to be exhaustive and is not to be taken as limiting the invention, but on the contrary is chosen with a view to illustrating my invention 25 so that others skilled in the art may apply it under varying conditions of practical use and may make such modifications and changes therein as such conditions may make desirable.

Figure 1 is a bottom plan view of a shoe with 30 one form of my reversible heel mounted thereon;

Figure 2 is a sectional view on the line 2—2 of Figure 1;

Figure 3 is a sectional view on the line 3—3 of Figure 2 showing the heel retaining nut in disconnected position;

Figure 4 is a perspective view of a plate for connecting the heel with a shoe;

Figure 5 is a sectional view similar to Figure 2, showing a modified construction, and

40 Figure 6 is an exploded perspective view of said modified construction.

On the accompanying drawing, I have used the reference character S to indicate generally a shoe. The sole portion thereof is indicated at 10 45 and the heel portion at 12. My reversible heel member is indicated generally at H. For mounting it on the heel portion 12 of the shoe S, I provide a perforated plate 13 and a flanged nut 14. The plate 13 is secured as by rivets or nails 15 to 50 the heel portion 12 of the shoe. Extending downwardly from the plate 13 is a threaded stud 16 received in the nut 14.

The heel member H may be made of rubber, leather, composition or the like, and includes a 55 bore 17 for the shank of the flanged nut 15. A

counterbore 18 formed in the heel member H receives the flange of the nut.

The flange of the nut is provided with perforations 19 adapted to receive a spanner wrench 20, as shown in Figure 3, for attaching or detaching the nut relative to the stud 16.

To prevent the heel member H from undesirable rotation and thus keep it aligned with the outline of the heel portion of the shoe, as shown in Figure 1, I provide a pair of integral wedge 10 shaped projections 21 on the lower surface of the plate 13. The projections 21 have their thin ends adjacent the stud 16 and their thick ends extended beyond the periphery of the plate 13. The heel member H has a pair of recesses 22 of substantially the same shape as the projections 21. When the heel member H is in assembled position on the heel portion 12 of the shoe S, these recesses snugly receive the projections 21, thus serving to insure against any rotation whatever 15 of the heel H relative to the shoe S.

The heel H has a worn portion indicated at 23 in Figure 1, which portion was the result of being originally positioned at 24. Figure 1 illustrates the heel after it has been worn in this manner 25 and turned so that the opposite edge of the heel may be at the point of greatest wear, indicated by the dotted portion 24. This arrangement substantially doubles the life of the heel.

In Figures 5 and 6, I show a construction 30 adapted to substantially quadruple the life of the heel. The heel is indicated at H' and is circular rather than oval as in Figure 1. It has other parts corresponding to those described in Figures 1 to 4 which bear the same reference numerals 35 with the addition of a. It will be noted that there is only one projection 21a, but there are four recesses 22a. I find that although two projections 21 are desirable, one is sufficient if it is desirable to manufacture my invention at less expense. By 40 providing four of the recesses 22a, the heel H' may be turned only a quarter turn each time and thus four edges of it can be worn off before it is necessary to discard the heel. When it is necessary to discard it, then the operation of attaching 45 a new heel is extremely simple.

By making the projection 21 wedgelike, its greatest depth in the heel member H is at its outer end, so as to give good leverage and a good grip in the depression 22 of the heel member to 50 positively prevent any undesired rotation of the heel member relative to the shoe. It is not necessary, however, that the plate 13 be extended to a diameter coincident with the distance across the ends of the projection 21 and 55

accordingly, by arranging the projection on the lower surface of the plate, the plate itself can be readily countersunk in a circular countersunk portion of the heel portion 12 of the shoe without having to go to the extra trouble of curving such passageways to receive the portions of the projections extended beyond the periphery of the plate 13.

Having described two specific embodiments of my invention together with the operation thereof, I desire it to be understood that these forms are selected merely for the purpose of facilitating disclosure of the invention rather than for the purpose of limiting the number of forms which it may assume. It is to be further understood that various modifications, adaptations and alterations may be applied to the specific forms disclosed to meet the requirements of practice without in any manner departing from the spirit and scope of the present invention except as set forth in the claims appended hereto.

I claim as my invention and desire to secure by Letters Patent of the United States:

1. In a reversible heel, a perforated plate 25 nailed to the heel portion of a shoe, a threaded stud extending downwardly therefrom, a reversible heel member having a central opening receiving said stud, said opening being larger than said stud, a flanged nut on said stud having a shank in said opening, said heel member having a counterbore to receive the flange of said flanged nut and means to prevent said heel member from turning relative to said plate comprising a projection from said plate and a plurality of circumferentially spaced radially extending depressions in said heel member adapted to selectively coact with said projection, said projection being wedgelike, being arranged radially on the lower surface of said plate and having a portion projecting beyond the periphery thereof.

2. In a reversible heel, a stud affixed to the heel portion of a shoe and extending down-

wardly therefrom, a reversible heel member having a central opening receiving said stud, means to retain said heel member on said stud and means to prevent said heel member from turning relative to said stud comprising a projection from said stud and a plurality of circumferentially spaced depressions in said heel member adapted to selectively coact with said projections. 5

3. In a reversible heel, a plate secured to the heel portion of a shoe, a threaded stud extending downwardly therefrom, a reversible heel member having a central opening receiving said stud, a nut on said stud to retain said heel member thereon, said nut being countersunk in 15 said heel member, and means to prevent said heel member from turning relative to said plate comprising a tapered projection from said plate and a plurality of circumferentially spaced depressions in said heel member adapted to selectively receive said projection, said projection being integral with and located on the lower surface of said plate and having its thin end adjacent said stud and its thick end extending beyond the periphery of said plate and said depressions being similarly tapered to fit said projection snugly. 20

4. In a reversible heel, a plate secured to the heel portion of a shoe and having a stud extending downwardly therefrom, a reversible heel member having a central opening receiving said stud, means on said stud to retain said heel member thereon and means to prevent said heel member from turning relative to said plate comprising a tapered projection from said plate and a plurality of circumferentially spaced depressions in said heel member adapted to selectively receive said projection, said projection extending beyond the periphery of said plate and said depressions being tapered similarly to said projection to fit it snugly. 30 35 40
